UNITED STATES PATENT OFFICE.

WILLIAM C. GEORGE, OF CLATONIA, AND FRED N. NOFSGER, OF HUMBOLDT, NEBRASKA.

WHEEL HUB.

Application filed January 16, 1922. Serial No. 529,733.

To all whom it may concern:

Be it known that we, WILLIAM C. GEORGE and FRED N. NOFSGER, citizens of the United States, residing respectively, at Clatonia, in the county of Gage, and Humboldt, in the county of Richardson, and State of Nebraska, have invented certain new and useful Improvements in Wheel Hubs; and we do declare the following to be a full, clear, and exact description of the invention, such as will enable others skilled in the art to which it appertains to make and use the same.

This invention relates to an improved wheel hub and one object of the invention is to provide a hub so constructed that an outer spoke carrying portion may be removably secured about an inner spindle engaging portion and to provide improved means for securely but releasably holding the outer spoke carrying portion in place upon the inner portion.

Another object of the invention is to provide securing means for the outer hub section including bolts for passing through registering openings in the two hub sections and blocks which will be removably mounted in pockets formed in the inner hub section and releasably held in these pockets in an improved manner.

Another object of the invention is to so construct and mount the blocks and so construct the pockets in which the blocks are mounted that the blocks may be held against dropping out of the pockets when the blocks are placed in the pockets and moved to a lockable position, the blocks being provided with side arms for fitting into recesses leading from the pockets and wedging means being provided for holding the blocks against movement towards a position in which they may be tilted and lifted out of the pockets.

Another object of the invention is to provide an improved hub construction which will permit of the outer spoke carrying section being easily placed upon the inner section and forced into tight binding engagement with this inner section by means of the fastener screws which have their inner

end portions screwed into the blocks, these fastener screws serving to hold the outer section in place and also serving to prevent relative rotation of the outer section upon the inner section.

This invention is illustrated in the accompanying drawings, wherein:

Figure 1 is a view showing the improved hub in vertical section.

Figure 2 is a sectional view taken along the line 2-2 of Fig. 1.

Figure 3 is a sectional view taken along the line 3-3 of Fig. 1.

Figure 4 is a fragmentary view showing the hub in section and one of the metal blocks partially removed.

This hub is provided with an outer section 1 and an inner section 2, the outer section being termed the spoke-carrying section and the inner section the spindle-engaging section. The outer spoke-carrying section is provided with an inner flange 3 and an outer ring 4 which is connected with the inner flange 3 by bolts 5 so that the spokes 6 may be tightly clamped between the flange and ring. The inner spindle-engaging section fits upon the spindle 7 and is provided with a key-way 8 which will be positioned in co-operative relation to the key-way 9 of the spindle, thus permitting a key 11 to be passed through these key-ways to lock the inner hub section upon the spindle. It is of course obvious that in a mounting for a front wheel, it will be desirable to have the wheel turn freely upon the spindle in which case the brake drum key-ways and keys may be omitted and the usual roller bearings provided between the spindle and inner hub member so that the wheel may turn freely upon the spindle.

The inner face of the outer hub section is cut to provide stepped shoulders 12 and 13 and the outer face of the inner hub section is provided with stepped shoulders 14 and 15. It will thus be seen that the inner hub section will fit properly within the outer hub section but cannot be moved longitudinally thereof beyond a desired amount. It will be further noted that between the shoulders 13 and 15 and inner side faces of the two

sections, these sections are tapered longitudinally of the hub and spindle thus providing for wedging action to provide a tight fit when the outer hub section is secured upon 5 the inner hub section. This inner end portion of the inner hub section is provided with radiating rib elements 16 and the inner end portion of the outer hub section is provided with pockets 17 to receive these 10 ribs 16.

In order to securely hold the outer hub section upon the inner hub section, there has been provided securing means which is illustrated in Figs. 1, 2 and 4. This 15 securing means consists briefly of securing bolts 18 which are passed through aligned openings 19 and 20 formed in the two sections of the hub and are screwed into threaded openings formed in metal blocks 21 which are mounted in sockets 22 formed in the inner hub section. These blocks are of duplicate construction and each is provided with side arms 23 and 24 which fit into recesses 25 and 26 extended from the 20 ends of the pockets 22. From an inspection of Fig. 1, it will be noted that the block is shorter than the pocket 22 so that it can have movement longitudinally of the pocket when necessary. It will also be noted from an inspection 25 of this figure that the arm 24 is longer than the arm 23 and that the pocket or recess 26 is deeper than the recess 25. It will thus be seen that when inserting the block, it may be put in place with the arm 30 24 extending into the recess 26 and the block tilted as shown in Fig. 4 and then dropped down into the pocket and moved to the position shown in Fig. 1. The securing screw 35 27 will then be screwed into the threaded opening formed in the arm 26 and as it is screwed tightly into place, the tapered head of the screw will form a wedging element which will engage the end of the block and the inner end of the pocket 22 and thus 40 45 tightly wedge the block in place. With the screw 27 removed, the block can be moved to extend the arm 24 inwardly of the recess 26 and the block can then be tilted upwardly to the position shown in Fig. 4 and 50 removed.

When assembling the wheel hub, the blocks 21 are first put in place and the securing screws 27 then inserted and screwed tightly into place so that the blocks will be firmly 55 wedged in the pockets. The outer hub section can then be placed upon the inner hub and the securing bolts 18 passed through the aligned openings 19 and 20 and screwed into the blocks 21. When these bolts are tightened, the outer hub section will be forced 60 towards the inner end of the inner hub section and the radiating arms 16 will be firmly wedged in the recesses 17 thus providing a good fit and preventing any relative movement between the two hub sections. When 65

it is desired to remove the wheel and put a new one in place, it is simply necessary to remove the bolts 18. The wheel can then be removed with the inner hub section left upon the spindle and a new wheel put in place. Therefore when a puncture is received, it is only necessary to remove the wheel and put a new one in place. This can be easily and quickly done. 70

We claim:

1. In a demountable wheel, a hub structure including an inner spindle-engaging section and an outer spoke-carrying section fitting upon the inner section, the sections having their contacting faces provided with 80 contacting abutment shoulders adjacent the inner and outer ends of the hub structure, blocks positioned in pockets formed in the inner hub section, and fasteners passing through aligned openings in the hub sections 85 and having their inner end portions engaging said blocks.

2. In a demountable wheel, a hub structure including an inner spindle-engaging section and an outer spoke-carrying section 90 fitting upon the inner section, the sections having their contacting faces provided with contacting abutment shoulders limiting longitudinal movement of the sections and having stepped relation to each other, one of the sections having pockets intermediate its shoulders, blocks removably fitting into the pockets, and fastener bolts passing through aligned openings in the hub sections and 95 screwed into threaded openings in said 100 blocks.

3. The structure of claim 2 having the blocks each provided with side arms fitting into recesses leading from the pocket, and securing means for holding the block against 105 movement out of the pocket carried by one of the side arms and engaging the inner hub section.

4. The structure of claim 2 having the blocks each provided with side arms fitting 110 into recesses leading from the pocket, the pocket being of greater length than the block and one arm having greater length than the other whereby the block may have movement longitudinally in the pocket with 115 the arms both in the recesses when the block is moved to one end of the pocket, and one of the arms out of its recess when the block is moved to the other end of the pocket and permitting tilting removal of the block and a fastener having threaded engagement with one arm and wedging engagement with the block and end wall of the pocket to hold the block against movement towards a position for removal. 120

5. The structure of claim 2 having the blocks each provided with side arms fitting 125 into recesses leading from the pocket, the pocket being of greater length than the block and one arm having greater length 130

than the other whereby the block may have movement longitudinally in the pocket with the arms both in the recesses when the block is moved to one end of the pocket and one of the arms out of its recess when the block is moved to the other end of the pocket and permitting tilting removal of the block,

and means for holding the block against movement towards a position for removal.

In testimony whereof we have hereunto set our hands.

WILLIAM C. GEORGE.
FRED N. NOFSGER.
